(57) **CLAIM**

The ornamental design for the bed caster cushion, as shown and described herein.

DESCRIPTION

FIG. 1 is a front perspective view of a bed caster cushion showing my new design in a closed position;

FIG. 2 is a front elevational view thereof;

FIG. 3 is a rear elevational view thereof;

FIG. 4 is a top plan view thereof, the broken lines of a caster shown in the square are for illustrative purposes only and form no part of the claimed design;

FIG. 5 is a bottom plan view thereof, the broken lines of a caster shown in the square are for illustrative purposes only and form no part of the claimed design;

FIG. 6 is a right side elevational view thereof; and,

FIG. 7 is a left side elevational view thereof.
